UNITED STATES PATENT OFFICE.

LINNAEUS T. SAVAGE, OF NEW YORK, N. Y.

DESIGN FOR A MATCH-SAFE.

44,451.

Specification for Design.

Patented Aug. 5, 1913.

Application filed May 22, 1913. Serial No. 769,301. Term of patent 7 years.

To all whom it may concern:

Be it known that I, LINNAEUS T. SAVAGE, a citizen of the United States, and residing at New York, in the county of New York and State of New York, and whose post-office address is No. 5 Beekman street, in the city of New York, State of New York, have invented a new, original, and ornamental Design for a Match-Safe, of which the following is a specification, reference being had to the accompanying drawings, forming part thereof.

Of the accompanying drawings illustrating my design as aforesaid: Figure 1 is a

front elevation of a match safe, showing my new design; and Fig. 2 is a side elevation corresponding to Fig. 1 from line A—B to the bottom of the figure.

I claim:

The ornamental design for a match safe as shown.

In testimony whereof I have signed my name to this specification, in the presence of two subscribing witnesses.

LINNAEUS T. SAVAGE.

Witnesses:

JOHN D. MORGAN,
ROSE MENK.
